UNITED STATES PATENT OFFICE.

JAMES REES, OF PITTSBURG, PENNSYLVANIA.

STEERING APPARATUS.

SPECIFICATION forming part of Letters Patent No. 253,226, dated February 7, 1882.

Application filed September 10, 1881. (No model.)

To all whom it may concern:

Be it known that I, JAMES REES, of Pittsburgh, in the county of Allegheny and State of Pennsylvania, have invented a new and useful Improvement in Steering Apparatus; and I do hereby declare that the following is a full, clear, and exact description thereof, reference being had to the accompanying drawings, and to the letters of reference marked thereon.

My invention relates to an improvement in steering apparatus; and it consists in compounding the leverage of the tiller, whereby it exerts an increased power in manipulating a series of rudders in the steering of water-craft, as will hereinafter more fully and at large appear.

To enable others skilled in the art with which my invention is most nearly connected to make and use it, I will proceed to describe its construction and operation.

In the accompanying drawings, which form part of my specification, Figure 1 is a perspective view of the hull of a vessel provided with my improvement in steering apparatus. Fig. 2 is a vertical section of the same at line *y y* of Fig. 3. Fig. 3 is an end elevation of the same.

The ordinary method of connecting the tiller to the rudder-stock is to form a mortise in the latter and secure the former permanently therein by means of keys or otherwise. This method of connecting the tiller involves the necessity of applying great force to the tiller for the purpose of manipulating the rudder, and often requires the pilot to throw the rudder into the desired position prior to any back movement of the vessel, otherwise it would be almost impossible to manipulate it when backing the vessel.

My invention has for its object the manipulation of the rudder with ease in either a backing or forward movement of the vessel. To accomplish this desirable result I extend the tiller beyond the pintle of the rudder, and pivoting it to an arm extending aft of the rudder-stock, with the tiller vibrating upon a center forward of said rudder-stock, and when two or more rudders are employed coupling them together by means of coupling-links pivoted to arms extending aft of said rudder-stocks.

Reference being had to the accompanying drawings, *a* represents the aft portion of the hull of a vessel; *d*, the skegs, to which the rudder-stocks *c* are pivoted, by means of pintles *f* and stirrups, in the usual manner.

To the rudder-stocks *c* of the rudders *i* and *i'* are secured arms *j*, which are aft of and at right angle to said stocks, and are coupled together by means of links *l*, pivoted to said arms, as indicated at *k*. The rudders *i'* are known to the art as "knuckle-rudders," and the rudder *i* as the "balance-rudder."

To the upper end of the stock *c* of the rudder *i*, and at right angle to said stock, and extending aft of it, is an arm, *h*, to which is pivoted at *g* the extension *b'* of the tiller *b*, which vibrates upon a center, *e*, projecting vertically from a cap, *m*, secured to the middle skeg *d*.

From the foregoing description the skillful boat-builder will readily understand the construction of my improvement and the relation that the several parts bear to each other. I will therefore proceed to describe the operation.

When the tiller *b* is moved to the starboard the rudders *i* and *i'* will be moved to the larboard, and when the tiller *b* is moved to the larboard the rudders *i* and *i'* will move to the starboard. The extension *b'*, being pivoted at *g* to the arm *h*, will give to the tiller a compound leverage in manipulating the rudder *i*, and by coupling the rudders *i* and *i'* to the rudder *i*, through the medium of the arms *j* and links *l*, pivoted as at *k*, a compound leverage of the tiller is applied to the three rudders shown in the present case.

Having thus described my improvement, what I claim as of my invention is—

In a steering apparatus, the combination of the series of rudders and stocks *c c c*, having fixed arms *j* projecting aft of said stocks, and links *l l* for connecting said arms, and the tiller fulcrumed forward of one of the stocks, having an arm, *h*, projecting aft of it, and said tiller having an extension connected to said arm *h*, substantially in the manner as and for the purpose herein shown and described.

JAMES REES.
